VENT FOR CONTAINERS

Charles H. Rollason, Wheeling, W. Va., assignor
to Wheeling Steel Corporation, Wheeling,
W. Va., a corporation of Delaware

Application October 28, 1932, Serial No. 639,987

10 Claims. (Cl. 221—28)

The present invention relates broadly to the art of shipping and storing receptacles, containers or the like, and more particularly to a vent adapted to be applied to containers of the character adapted for the dispensing of fluids.

It has heretofore been proposed in the art to which the present invention relates to provide fluid shipping, storing and dispensing containers with vents of different types. In many cases the vent has comprised an opening remote from the pouring opening or spout, and adapted to be closed by means of a suitable plug. In other cases the vent has been in the form of a depression at a suitable point in the container adapted to be punctured prior to discharging the contents from the container. In still other cases the structure has comprised a specially constructed vent tube or the like built into the container as an integral part thereof at the time of its manufacture.

To those skilled in the art, it will be appreciated that it is customary in the production of containers to manufacture more or less standard covers in large quantities, and then apply such covers or heads to different containers. In some cases a user will desire a vent in a cover while in other cases the vent may not be specified. It is therefore desirable, and the invention has for one of its objects, to provide what may be termed a detachable vent which may be applied to a wide variety of covers or heads previously manufactured, and prior to their assembly on container bodies.

In this manner, a single set of dies may be utilized for the manufacture of standard heads, and these heads may then be used, at the pleasure of the manufacturer, in accordance with orders received by him, either with or without vents.

In this manner the carrying in stock of a large number of different types of covers some with and some without vents may be obviated, and the manufacturing cost of containers may be considerably reduced since standard dies are made more readily available.

In the accompanying drawing I have shown more or less diagrammatically, and for purposes of illustration only, certain preferred embodiments of the present invention. In the drawing:—

Figure 1 is a detail sectional view, partly in elevation, through one form of head having my detachable vent in position therein, the parts being illustrated in position ready for pouring;

Figure 2 is a view similar to Figure 1, illustrating the parts in position for shipment;

Figure 3 is a top plan view of the pouring spout and a portion of the vent shown in Figure 1;

Figure 4 is a detail section of the vent detached from a container;

Figure 5 is a view similar to Figure 4 illustrating a modified embodiment of my invention; and

Figure 6 is a detail sectional view along the line VI—VI of Figure 5, looking in the direction of the arrows.

Before proceeding with the detail description of my improved vent, I wish it to be understood that the vent is of such construction that it may be applied to covers or heads of a wide variety of different types, so that the portion of the container herein illustrated is not to be considered as in any wise limiting the invention.

Having reference more particularly to Figures 1 and 2 of the drawing, I have illustrated a more or less common form of head or cover 2 having a pouring spout or opening 3 suitably secured in position therein adjacent one edge of the cover in convenient location for pouring. The head or cover is shown associated with a container body, it being understood that it is adapted for application to a body of any desired type or construction.

The pouring spout, while it might constitute an integral part of the cover, is herein illustrated as comprising a separate member suitably seamed or crimped into position and threaded to receive a closure cap 4. The inner portion of the spout is conveniently shaped to provide a restricted pouring opening 5 terminating in a pouring lip 6. The neck and lip are herein illustrated as being formed by a reversely bent or downwardly and inwardly projecting skirt-like portion 7. Such a reversely bent portion provides an annular space 8 surrounding the pouring opening 5. While the utility of the invention is not limited to special pouring spouts of this construction, it is particularly adapted thereto since the downturned portion 7 forms a partially protective housing, as will be hereinafter more fully understood, for the retaining means for the vent.

This vent is herein illustrated as comprising a vent tube of generally rectangular cross section having a substantially horizontally disposed portion 9 underlying the cover and an upwardly extending portion 10 adapted to lie within the pouring neck 5. An extension 11 on the portion 9 forms a pivotal mounting for the vent tube, this mounting cooperating with a transversely extending portion 12 of a spring wire mounting and retaining member. This retaining member at

one side of the portion 9 is provided with a forwardly extending arm 14 terminating in a transversely bent portion 15 underlying the part 9 of the vent tube and exerting an upward pressure thereon effective for swinging the vent tube from the position illustrated in Figure 2 into the position illustrated in Figure 1 as soon as the closure 4 is removed.

Along the opposite side of the vent tube the 10 spring holding and retaining member is formed with an arm 16 extending to a point adjacent the portion 10 of the tube and then across the tube and terminating in a curved pouring nozzle engaging portion 17. Normally the portion 17 occupies the position illustrated in full lines in Figure 4, but when contracted into the dotted line 15 position of this figure may be easily slipped into position within a pouring spout of any desired contour or construction, the outward expansion thereof holding the parts in position with sufficient rigidity for the purposes contemplated.

From the foregoing description it will be apparent that I have provided a detachable vent which may be quickly applied to a container of either standard or special construction, and held 25 therein in such relation that upon removal of the closure the free end of the vent tube will project upwardly out of the container into a region where an ample supply of venting air is available.

In Figures 5 and 6 there is shown, by way of 30 illustration only, another embodiment of the invention. In accordance with this embodiment, the vent tube 18, which may be of exactly the construction before described, is mounted on a retaining member comprising spaced arms 19 each terminating in a curved mounting portion 20. These portions normally occupy the position illustrated in full lines in Figure 5, but may be easily compressed into the position indicated 35 in dotted lines for insertion into a spout or pouring opening.

The desired spring pressure for urging the 40 vent into pouring position corresponding to Figure 1, may be obtained, in such a structure, by a separate spring member 21 carried by the vent tube and adapted to engage the under side of the cover for normally urging the free end 22 upwardly as soon as the closure is removed.

It will further be understood that the detachable vent herein illustrated may be utilized with 45 equal facility and advantage in a container of the type having not only a normal closure of the character indicated, but also a separate inner seal adapted to permit dispensing the contents 50 of the container only when it has been ruptured or removed.

The advantages of the present invention arise 55 from the provision of a detachable vent, regardless of its particular construction or contour, adapted to be detachably secured in position to the pouring opening of a container, and especially where it includes a mounting of such nature as to tend to swing a portion of the vent upwardly into a position where it is entirely free from 60 any choking tendency by the liquid being dispensed.

While I have herein illustrated and described 65 certain preferred embodiments of my invention, it will be understood that changes in the construction and arrangement of the parts may be made without departing either from the spirit

of my invention or the scope of my broader claims.

I claim:

1. The combination with a receptacle having a pouring opening of a vent disposed in venting relation to said opening, means for attaching the vent to the receptacle cooperating with the receptacle adjacent the pouring opening, and a pivotal connection between the vent and said means.

2. The combination with a receptacle having a 10 pouring opening of a vent disposed in venting relation to said opening, means cooperating with the receptacle for attaching the vent to the receptacle, and resilient means additional to said first mentioned means for urging the vent to 15 operative position.

3. The combination with a receptacle having a 20 pouring opening of a vent disposed in venting relation to said opening, means cooperating with the receptacle for attaching the vent to the receptacle, there being a pivotal connection between the vent and said means, and resilient means additional to said first mentioned means for urging the vent to operative position.

4. The combination with a pouring spout of a 25 spring mounting member detachably engaging the spout, and a vent carried by said spring mounting member.

5. The combination with a receptacle cover having a pouring opening of a vent tube having 30 a portion underlying said cover and a second portion constructed and arranged to vent through said opening, and means for detachably securing said vent in venting relation to said opening, said means including a spring mounting member 35 adapted to be engaged about said opening.

6. The combination with a receptacle having a 40 pouring opening of vent means and attaching means for attaching the vent means to the receptacle, the attaching means being so constructed and arranged as to effect attachment by resilient cooperation with the receptacle at the pouring opening.

7. The combination with a receptacle having a 45 preformed pouring opening of vent means and attaching means for attaching the vent means to the receptacle, the attaching means being so constructed and arranged as to effect attachment by cooperation with the receptacle at the pouring opening without deformation of the receptacle 50 and being detachable therefrom.

8. The combination with a receptacle having a 55 pouring opening of vent means and attaching means for attaching the vent means to the receptacle, the attaching means comprising a portion adapted to snap into place to attach the vent means to the receptacle.

9. The combination with a receptacle having a 60 pouring opening of vent means and attaching means for attaching the vent means to the receptacle, the attaching means comprising a portion adapted to snap into place about the pouring opening.

10. The combination with a receptacle having a 65 pouring opening of vent means and attaching means for attaching the vent means to the receptacle, the attaching means cooperating with the receptacle at the pouring opening and resiliently holding the vent means in place.
